COMBINED MIRROR AND FLASHLIGHT

Kyran M. Murphy, Altamonte Springs, Fla.
(1011 Arlington Blvd., Apt. 1106W, Arlington, Va. 22209)

Filed Aug. 28, 1970, Ser. No. 24,740

Term of patent 14 years

Int. Cl. D6—07

U.S. Cl. D86—10

FIG.1

FIG.5

FIG. 1 is a top plan view of a combined mirror and flashlight showing my new design;

FIG. 2 is a front elevational view thereof;

FIG. 3 is an end elevational view taken from the left of FIG. 2; and

FIG. 4 is an end elevational view taken from the right of FIG. 2.

I claim:

The ornamental design for a combined mirror and flashlight, substantially as shown.
